M. C. RYPINSKI

RADIOREPRODUCER

Filed Aug. 6, 1925

INVENTOR.

Maurice C. Rypinski,
BY John C. Brady.
ATTORNEY.

UNITED STATES PATENT OFFICE.

MAURICE C. RYPINSKI, OF YONKERS, NEW YORK.

DESIGN FOR A RADIOPRODUCER.

Application filed August 6, 1925. Serial No. 14,327. Term of patent 14 years.

To all whom it may concern:

Be it known that I, MAURICE C. RYPINSKI, a citizen of the United States of America, residing in Yonkers, county of Westchester, and State of New York, have invented a new, original, and ornamental Design for a Radioproducer, of which the following is a specification, reference being had to the accompanying drawing, forming part thereof.

The figure is a perspective view of the radioproducer showing my new design.

I claim:

The ornamental design for a radioproducer as shown.

MAURICE C. RYPINSKI.
